UNITED STATES PATENT OFFICE.

MICHAEL J. WHELAN, OF MUSKEGON, MICHIGAN, ASSIGNOR TO BRUNSWICK-BALKE-COLLENDER CO., A CORPORATION OF DELAWARE.

CLOSET-SEAT AND THE LIKE.

1,206,186.

Specification of Letters Patent. Patented Nov. 28, 1916.

Application filed July 14, 1913. Serial No. 778,982.

To all whom it may concern:

Be it known that I, MICHAEL J. WHELAN, a citizen of the United States, and a resident of the city of Muskegon, in the county of Muskegon and State of Michigan, have invented certain new and useful Improvements in Closet-Seats and the like; and I do hereby declare that the following description of my said invention, taken in connection with the accompanying sheets of drawings, forms a full, clear, and exact specification, which will enable others skilled in the art to which it appertains to make and use the same.

This invention relates generally to improvements in closet seats and the like, and it consists, essentially, in the novel and peculiar combination of parts and details of construction, as hereinafter first fully set forth and described and then pointed out in the claim.

In the drawings already referred to which serve to illustrate my said invention more fully, Figure 1 is a vertical, longitudinal section of a closet seat and cover embodying my invention. Fig. 2 is a plan of a closet seat frame before the application of my invention. Fig. 3 is a cross section on line 3—3 of Fig. 2 with my invention applied thereto. Fig. 4 is a fragment of Fig. 1 on an enlarged scale. Fig. 5 is a section on line 5—5 Fig. 2 showing said section in its finished condition. Fig. 6 is a similar section on lines 6—6 of Fig. 2 and Fig. 7 is a section on line 7—7 of Fig. 2.

Like parts are designated by corresponding characters or symbols of reference in all the figures of the drawings.

It is the aim and essence of my invention to produce a seat and cover therefor that is positively immune from germ impregnation; a seat and cover which will always remain sweet; one in which all fecal matter may be removed therefrom without affecting the finish, appearance, or sanitary qualities thereof, and an article of superior appearance and lasting qualities.

Briefly the seat, comprising part of my invention, consists of a wooden frame of the usual appearance, except that it is made of the cheapest class of wood roughly framed together; no attention being paid to the accuracy of joints in the framing nor the closeness of fits in the tenons used in framing. The parts are held together by

a few pegs driven at proper points and no glue is employed; nor is there any smoothing of the surface attempted, the faces of the frame still showing the saw and tool marks. In this condition the frame is covered with a heavy coating of rubber composition in a plastic state, and the whole is then introduced into a suitable two part vulcanizing mold. This mold is possessed of a cavity the exact duplicate of a finished seat and the two parts thereof are next tightly screwed together, thereby creating a great pressure upon all parts of the mass within the same. Said mold is subjected to great heat for a suitable length of time and then allowed to cool, after which the finished seat is removed therefrom. Said seat now presents a black appearance. The rubber composition (now termed vulcanite) has entirely incased the wood frame and hermetically sealed the same within the coating. All open joints in the framing or tenons and all checks or knots in the wood have been thoroughly filled with the vulcanite, which, at the same time has also actually penetrated the surface of the wood a certain distance, so that the structure is now to all intents and purposes an integral homogeneous mass. This creates an integral bond which inseparably joins the surface of the wooden core to the closely contacting surface of the rubber envelop and is composed of minute interfitting permanently united particles of both the wood and rubber surfaces. The vulcanite may be burnished in a close imitation of ebony and the resultant product is one of handsome appearance and unusual strength and lasting qualities, in addition to being absolutely sanitary. The cover is treated in the same manner, except that its frame is not provided with a central opening as is the seat.

For further details of my invention, attention is now directed to the drawings in which C represents the finished cover and S the similarly prepared seat; V and V' represent the vulcanite covering hermetically inclosing said cover and seat respectively.

F, Fig. 2 indicates the rough wooden seat frame comprising side members 1 and 2 and ends 3 and 4, the whole being framed together by tenons 5, 6, 7, and 8 and dowel pins 9. The numeral 10 refers to the open joints between the sides and end rails 1 and

2 and 3 and 4. These openings are slightly exaggerated in the drawings and are meant to elucidate the fact that accuracy of workmanship in framing the parts is not necessary. A check in the wood is shown at 11, and a knot at 12 Figs. 2, 5, and 6, the last named of which illustrates how the rubber composition enters these cavities, is vulcanized therein, and actually penetrates the 10 surrounding fiber of the wood. O is a central opening in frame F of seat S, provided for obvious purposes. The interior blank I of cover C is prepared in precisely the same manner as frame F, except that the 15 central opening O is not formed therein.

On the under faces of the seat S and cover C are provided a plurality of vulcanite lined essentially spherical depressions 13 which are provided with necks 14 of smaller diameter. These depressions are provided for the 20 reception of heads 15 of cushioning buttons 16. These buttons are made from comparatively soft rubber and the heads 15 thereof are capable of being compressed sufficiently 25 to pass through necks 14, after which said heads expand and fill the depressions 13, thereby securely retaining said buttons 16 firmly in place. The object of said buttons 30 is to cushion the jar occasioned by dropping the seat upon the top of a closet bowl or of dropping said cover upon said seat.

Seat O and cover C may be hinged together by any suitably formed hinge H, comprising leaves 20 and 21 and pintle 22. 35 I wish to call attention to the fact that the practice of my invention is not limited

to closet seats alone, but may be applied to other wooden shapes or blanks wherein the practical union of the inner wooden blank and outer vulcanite covering would be advantageous. 40

While I have herein described the preferred method of carrying my invention into effect, I wish it understood that I may make such changes and alterations as are within the scope of the skilled mechanic and permitted under the doctrine of mechanical equivalents. 45

Having thus fully described my invention, I claim as new and desire to secure to myself by Letters Patent of the United States: 50

The herein-described method of making closet seats which consists in providing a core composed of a plurality of rough-surfaced wood sections loosely fitted and 55 connected together, then entirely enveloping the core in a covering of rubber composition in a plastic state, subjecting the same to heavy pressure to force the rubber composition into the joints between the sections and into the rough surface of the core, then subjecting the same to a vulcanizing heat while maintaining said pressure, and then burnishing the seat. 60

In testimony whereof I have hereunto set 65 my hand in the presence of two subscribing witnesses.

MICHAEL J. WHELAN.

In the presence of
F. J. LOEWE,
J. O. MATTESON.
